SUCTION NOZZLE

Lars Johan Faith Ell, Stockholm, Sweden, assignor to Electrolux Corporation, Dover, Del., a corporation of Delaware

Application June 26, 1936, Serial No. 87,390
In Switzerland July 2, 1935

2 Claims. (Cl. 15—155)

My invention relates to suction nozzles for use in connection with a vacuum cleaner and particularly to a nozzle which automatically changes the size of the suction opening therein.

5 Heretofore there have been known so-called duplex nozzles which may be changed at the will of the operator so as to have either a large suction opening and consequently a more widely distributed flow of air, or a small suction opening 10 with a concentrated flow of air. The first type of opening is advantageously used in ordinary cleaning, as it permits covering of a relatively large surface to be cleaned within a short length of time. When objects, such as threads, are en- 15 countered which the distributed flow of air is unable to pick up, the operator shifts the nozzle so as to obtain a concentrated flow of air.

One of the objects of my invention is to provide a nozzle of the above general type, but one 20 in which the size of the opening is automatically altered during each complete stroke of the nozzle. For instance, on the forward stroke of the nozzle a restricted opening is provided while on the return stroke a large opening is provided. 25 The advantage of this is that a large surface can be cleaned in a relatively short length of time, while at the same time a concentrated flow of air is intermittently established without the conscious effort of the operator. This concentrated flow of air picks up articles not en- 30 trained by the more distributed flow, whether such articles are seen by said operator or not.

The objects and advantages of my invention will be apparent from the following description 35 considered in connection with the accompanying drawing which form part of this specification, and of which:

Fig. 1 is a cross-sectional view of a preferred embodiment of my invention;

40 Fig. 2 is a cross-sectional view taken on the line 2—2 of Fig. 1;

Fig. 3 is a view similar to Fig. 2 but showing the parts in a different position; and

Fig. 4 is a bottom view of a portion of the 45 nozzle shown in Figs. 1 and 2.

Referring to the figures, reference character 10 designates an elongated nozzle body provided with an elongated suction opening 11. Rigidly secured to or integral with body 10 is a hollow nipple 12 adapted to be connected by a conduit 13 to a source of suction. Usually conduit 13 is rigid so as to provide a handle for moving the nozzle backwards and forwards over the surface to be cleaned. Nipple 12 communicates with the interior of body 10 through an opening 14. Pivoted within body 10 on a rod 15 is a flap valve member 16 having a front wall 17 longer than the diameter of opening 14, and end walls 18. The height of flap valve 14 is such that it pro-

jects slightly below the bottom of body 10 so as to contact the surface to be cleaned.

When the nozzle is moved forward over the surface to be cleaned in the direction indicated by the arrow in Fig. 2, valve 14 is pivoted to the rear of nozzle body until end walls 18 contact the rear wall of the body. Consequently, all of the air drawn into the nozzle must pass through the opening 20 defined by the walls of valve 14 and the rear lip of the nozzle. This results in a concentrated flow of air which is able to pick up articles such as threads which adhere to the surface.

When the nozzle is moved on the return stroke over the surface in the direction indicated by the arrow in Fig. 3, valve 16 is pivoted to the position shown in this figure and end walls 18 are spaced from the rear wall of the nozzle body, whereby communication is established between opening 14 and the entire extent of elongated 20 suction opening 11, thereby providing a flow of air distributed along the entire length of the nozzle.

While I have shown and described one more or less specific embodiment of my invention it 25 is to be understood that this has been done for purpose of illustration only, and that the scope of the invention is not to be limited thereby, but is to be determined by the appended claims.

What I claim is:

1. In a suction nozzle adapted to be moved forwards and backwards over a surface to be cleaned, a hollow body having an elongated suction opening, and a hollow valve member pivotally mounted within said hollow body and having an open end projecting through said suction opening so as to contact said surface and be pivoted by reversal in direction of movement of said nozzle, said valve in one position restricting the effective area of said suction opening to that of the open end of the valve member and in another position rendering the entire area of said suction opening effective.

2. In a suction nozzle adapted to be moved forwards and backwards over a surface to be cleaned, a hollow body having an elongated suction opening, and a hollow valve member pivotally mounted within said hollow body and having an open end terminating in surface contacting position adjacent to the plane of said suction opening and arranged so as to be pivoted by reversal in direction of movement of said nozzle, said valve in one position restricting the effective area of said suction opening to that of the open end of the valve member and in another position rendering the entire area of 50 said suction opening effective.

LARS JOHAN FAITH ELL.
